Primary Examiner — Sheryl Lane
Assistant Examiner — Nicole Shiflet(57) **CLAIM**

The ornamental design for a tube connector, as shown and described.

DESCRIPTION

FIG. 1 is a perspective view of a tube connector showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective view thereof; and,

FIG. 9 is an assembled view for showing the tube connector which is assembled with tubes.

The broken lines shown in the drawings show unclaimed subject matter only and form no part of the claimed design.
